UNITED STATES PATENT OFFICE.

MICHAEL J. BOYLE, OF CHICAGO, ILLINOIS.

POPPET VALVE.

Application filed June 21, 1922. Serial No. 569,989.

To all whom it may concern:

Be it known that I, MICHAEL J. BOYLE, a citizen of the United States, and resident of Chicago, county of Cook, and State of Illinois, have invented certain new and useful Improvements in Poppet Valves, of which the following is a specification, and which are illustrated in the accompanying drawings, forming a part thereof.

The invention relates to poppet valves for internal combustion engines, and has for its object to provide a valve which will be quiet in operation and of high efficiency and great durability, especially for controlling the exhaust ports of the engine. In the accompanying drawings:

Fig. 1 is a central sectional view showing the head and adjacent portion of the stem of the improved valve, with a detail of the valve seat;

Figs. 2 and 3 are plan views of elements employed in the construction of the valve head;

Fig. 4 is a plan view showing a pair of the valves of a modified form designed to control intake and exhaust ports of increased size without a corresponding increase in the amount of space occupied by the said ports and valves, and also showing a detail of the wall of the chamber in which the said ports are formed;

Fig. 5 is a detail side elevation of the valves illustrated in Fig. 4, with the associated valve seats shown in section;

Fig. 6 is a plan view of a valve having a head of another modified form, partly broken away to illustrate the interior construction of the head;

Fig. 7 is a detail side elevation of the valve illustrated in Fig. 6, with the associated valve seat shown in section; and

Fig. 8 is a side elevation, partly in section, showing a still further modification, with a detail of the associated tappet and cam.

On the drawings a portion only of an engine, which may be of the internal combustion type, is shown. Since the specific features of the engine constitute no part of the present invention it is not thought necessary to show those features. The invention relates more particularly to the construction of the valve and its relation to the engine.

The head of the valve is formed from a plurality of plates at least one of which is more or less resilient. While in the forms of

the device selected to illustrate the invention a plurality of resilient or elastic plates are employed, it is understood that the construction may be otherwise. As shown on the drawings, the valve head is of laminated structure, and comprises an intermediate group of relatively thin elastic sheet steel plates, as 10 and 11 (Figs. 1, 2 and 3). These plates are shaped to conform with the shape of the valve head, being round when a circular valve, as 12 (Fig. 1) or 13 (Fig. 8) is used, while similar plates 14, 15, of semi-circular outline are employed for the valves 16, 17 (Figs. 4 and 5), and square plates 18, 19, are employed for the valve 20 illustrated in Figs. 6 and 7. On the other hand, the several plates in each valve preferably vary slightly in size, those near the under side or seating face of the valve being largest, and the size of the remaining plates 75 being such as to provide the valve head with an upwardly facing beveled edge, as 21 (Fig. 1).

In addition to the intermediate group of thin plates, as 10, 11, the improved valve 80 head preferably includes a thicker plate 22 and a pair of tapering cap plates, as 23 and 24, between which the said group of thin plates and the plate 22 are held. When so constructed the plate 22 is located immediately under the group of thin plates, as 10, 11, and constitutes the seating or contact face of the valve head. Furthermore, since the invention contemplates the use of the valve in conjunction with a flat seat, as 25 85 (Figs. 1 and 8), 26 and 27 (Fig. 5), or 28 (Fig. 7), the said thicker plate, as 22, is desirably of a diameter at least as great as that of the immediately overlying thin plate, as 11,—being enough larger than the corresponding port opening, as 29, to provide the required amount of overlap upon the said flat seat, as 25. On the other hand, to permit elastic separation of the marginal portions of the remaining plates, and to provide 90 a clear opening through the port, as 29, when the valve is lifted, the diameter of the lower cap plate, as 23, is substantially less than that of the port.

Since the elastic separation of the marginal portions of the plates, as 10, 11 and 22, should be downwardly toward the valve seat, as 25, the upper cap plate, as 24, may be larger than the lower cap plate, as 23, and a tendency to shear the remaining plates is 110

2
avoided if the said two cap plates are of different size in any event. As shown in Figs. 1 and 8, the upper cap plate, as 24, is of such size that its edge extends substantially to the edge of the next underlying plate, as 10. The tapering form of the upper cap plate, as 24, accordingly continues the crowned shape in cross section imparted to valve head by the use of plates, as 10, 11, of 5 gradually diminishing size from the lower face of the valve upwardly. In the form of the device shown in Fig. 4, the cap plate overlaps the port to thereby further limit the resilient action of the intermediate plates. 10

15 In any event the marginal portions of the resilient plates are free,—that is, they are not connected together.

In practice, the several parts of the valve head are assembled upon the end of the valve 20 stem, as 30 or 31, preferably between an upwardly facing shoulder 32 formed on the stem adjacent its end, and a riveted head 33 at the end of the stem. In some instances, however, as shown in Fig. 1, a washer 34 25 may be placed over the upper cap plate, as 24, to receive the riveted head. It is also desirable to compress the stem for the formation of the said riveted head while the end portion of the stem and the central portions 30 of the several parts of the valve head are at a welding temperature. All of the parts of the valve head and the stem are thereby joined together in a unitary structure without interfering with the flexibility of the 35 marginal portions of the plates of which the head is composed. When unusual strength is required in the connection between the head and stem, some of the intermediate plates employed in the formation of the head 40 may each be provided with a central opening, as 35 (Fig. 8), larger than the valve stem. Compression of the end portion of the stem at a welding or forging temperature then serves to upset the stem within the 45 central openings 35 of the head plates, forming an enlarged hub, as 36, thereon intermediate the upper and lower faces of the valve head.

The intermediate plates 10 and 11, being 50 clamped at their central portions between the larger upper plate 24 and the smaller plate 23, will tend to cup downwardly, the said plates becoming slightly concave. Consequently, in operation, the peripheral 55 edge of the plate 22 will be the first portion of the valve to engage its seat, thereby forming a line contact which will efficiently close the port. But whether the resilient plate or plates are concave 60 or not, the explosion of the charge will cause the valves to be forced against their seats and the resiliency of the plates will permit a slight radial movement thereof which will not only prevent the accumulation 65 of carbon and other foreign matter be-

tween the valve and its seat, but will also tend to keep the valves polished or ground to perfectly fit their seats, thereby adding materially to the efficiency of the valve and effecting a consequent saving of fuel. 70

This type of valve operates much more quietly than the conventional type of poppet valve. The reason for this is probably due to the fact that in the conventional type the valve is more or less wedged in its conical seat by the tremendous pressure of the exploded gases to which it is subjected, and is rigidly held in that position by the pressure until the tappet strikes it. In the present device, the valve is not wedged in its seat, and, furthermore, the resiliency of the intermediate plates operating against this pressure tends to move the valve stem upwardly, thereby cushioning the initial engagement of the tappet with the valve. 75 Furthermore, the resiliency of the plates constituting the valve head cushions the impact of the valve with its seat and thereby tends to prevent noise of the valve during its seating movement. 80

90 It will thus be seen that the assembly of the parts and their arrangement are such that the resilient plates of the valve not only prevent the accumulation of carbon on the valve or its seat, but also automatically cushion the initial impact of the tappet with the valve and the valve with its seat during the operation of the engine. 95

The advantages obtained by the provision of a valve head of resilient laminated construction for cooperation with a flat seat are increased in some cases by the formation of some of the plates, as 10 (Figs. 1 and 2), 15 (Fig. 4), and 19 (Fig. 6), with apertures 37 adjacent the margins thereof, the 100 said apertures serving as pockets within which fluid becomes entrapped. As shown, the apertured plates 11, 15 and 19 are alternated with imperforate plates 10, 14 and 18, respectively, in the construction of the 105 corresponding valves. When this arrangement is used, capillary attraction and repeated exposure of the valve head to high 110 compression and suction both tend to the movement of fluid between the plates from the rim of the valve head to the pockets formed by the apertures 37, and this fluid serves to increase the elastic separation of the plates and to cushion their compression. 115

The construction of the valve head for 120 elastic expansion at its rim is particularly advantageous when the periphery of the valve is relatively long in comparison with the size of the port which it controls. Thus when the valve is semi-circular, as in Fig. 4, 125 or square, as in Fig. 6, the periphery of the valve is longer than that of a round valve covering a port opening of the same size. The force employed to close the valve is thus distributed over a greater area of con- 130

tact of the valve with its seat and the elastic separation of the parts of the valve head at its rim is more effective, both in cushioning the closing movement and insuring a 5 uniform contact with the valve seat. The use of semi-circular valves, as in Fig. 4, further provides for the location of intake and exhaust ports, as 38 and 39, of large size upon a limited area, and both the said semi-circular and square forms of the valve provide a greater area of opening between the valve and its seat, when the valve is lifted a given distance, than would be obtained with a circular valve covering a port 10 passage of the same size. It will also be observed that when the valve is used upon a flat seat, the width of the opening provided between the valve and seat is equal to the full distance through which the valve has 15 been lifted, while with an oblique seat of the usual form the width of valve opening is only equal to a part of the distance through which the valve has been lifted.

Owing to the elastic separation of the 25 plates or laminations of the valve head at its rim, changes in the length of the valve stem, due to expansion and contraction, will have substantially no effect upon the seating of the valve. The provision of clearance between the end of the valve stem, as 31, the 30 tappet, as 40, and the cam 41, will therefore be unnecessary. A noisy operation is thus avoided both by continuous contact between the valve stem, the tappet and the cam, and 35 by cushioning the closing movement of the valve as the elastically separated plates approach the valve seat.

I claim as my invention—

1. In combination, an inwardly facing flat 40 valve seat surrounding a gas engine port and a valve for the port comprising a group of centrally connected superimposed spring plates having their margins free, the undermost plate being larger than the port for 45 contact of a continuous marginal portion of its undersurface with the valve seat under gas pressure applied to the group of plates in the direction to close the valve, and one of the intermediate plates having a circumferential series of apertures formed in its 50 marginal portion, but not extending to the periphery of the plate.

2. In combination, an inwardly facing flat 55 valve seat surrounding a gas engine port and a valve for the port comprising a group of centrally connected superimposed spring plates having their margins free and a stiff cap plate limiting upward flexure of the 60 marginal portions of the spring plates, the undermost spring plate being larger than the port for contact of a continuous marginal portion of its undersurface with the valve seat under gas pressure applied to the group of plates in the direction to close the 65 valve, one of the intermediate spring plates

having a circumferential series of apertures formed in its marginal portion but not extending to the periphery of the plate.

3. In combination, an inwardly facing flat 70 valve seat surrounding a gas engine port and a valve for the port comprising a group of centrally connected superimposed spring plates having their margins free, the undermost plate being larger than the port for contact of a continuous marginal portion of 75 its undersurface with the valve seat under gas pressure applied to the group of plates in the direction to close the valve, and each alternate intermediate plate having a circumferential series of apertures formed in 80 its marginal portion but not extending to the periphery of the plate.

4. In combination, an inwardly facing flat 85 valve seat surrounding a gas engine port and a valve for the port comprising a group of centrally connected superimposed spring plates having their margins free, the undermost plate being larger than the port for contact of a continuous marginal portion of 90 its undersurface with the valve seat under gas pressure applied to the group of plates in the direction to close the valve, and the remaining plates being of progressively diminishing sizes.

5. In combination, a flat circular valve 95 seating surface extending continuously about a pair of separate semi-circular gas engine ports and a valve for each port comprising a group of centrally connected superimposed spring plates of the same shape 100 as the port, the plates being unconnected in their marginal portions and the undermost plate of each group being larger than the corresponding port for contact of a uniform continuous marginal portion of its 105 undersurface with the said valve seating surface in the closed position of the valve.

6. A valve for internal combustion engines, comprising a valve stem, an abutment on said stem, a plurality of resilient plates 110 having their margins free, one of the side faces of one of said plates being adapted to engage a valve seat, and a rigid cap plate secured to said stem in the opposite side of said plates from the valve seat engaging face and adapted to clamp said plates against said abutment.

7. A valve comprising a valve stem, a resilient plate secured to said stem and having its margin free, one of the side faces of 120 said plate being adapted to overlap and engage a valve seat and a rigid plate secured to said stem and clamped against the side face of said plate opposite to the seat engaging face for reinforcing the same.

8. In a device of the class described, a valve comprising a stem, a plurality of resilient plates, said plates having their margins free, on said stem, the innermost plate being materially thickened, an inner 125

rigid plate, an outer rigid plate of larger diameter than said inner rigid plate, and means for clamping all of said plates on said stem.

5 9. In combination, an inwardly facing valve seat surrounding a gas engine port and a valve for the port comprising a stem, a group of superimposed spring plates having their margins free, said plates being 10 clamped together on said stem, the undermost plate being larger than the port for contact of a continuous marginal portion of its undersurface with the valve seat under gas pressure applied to the group of plates 15 in the direction to close the valve.

10 10. In combination, an inwardly facing valve seat surrounding a gas engine port and a valve for the port comprising a group 20 of centrally connected superimposed spring plates having their margins free and a stiff cap plate limiting upward flexure of the

marginal portions of the spring plates, the undermost spring plate being larger than the port for contact of a continuous marginal portion of its undersurface with the 25 valve seat under gas pressure applied to the group of plates in the direction to close the valve.

11. In combination, an inwardly facing substantially flat valve seat surrounding a 30 gas engine port, and a valve for the port comprising a centrally connected elastic sheet metal plate and superimposed stiff cap plate, the marginal portion of the sheet metal plate being free and resting upon the 35 valve seat in the closed position of the valve and the stiff cap plate serving to limit upward flexure of the said marginal portion of the sheet metal plate under gas pressure applied to the valve in the direction to close 40 the same.

MICHAEL J. BOYLE.
